UNITED STATES PATENT OFFICE.

GEORGE D. SCHLOSSER, OF SUNNYSIDE, WASHINGTON.

HARROW.

SPECIFICATION forming part of Letters Patent No. 738,361, dated September 8, 1903.

Application filed February 9, 1903, Serial No. 142,504. (No model.)

To all whom it may concern:

Be it known that I, GEORGE D. SCHLOSSER, a citizen of the United States, residing at Sunnyside, in the county of Yakima and State of Washington, have invented certain new and useful Improvements in Harrows; and I do declare the following to be a full, clear, and exact description of the invention, such as will enable others skilled in the art to which it appertains to make and use the same.

My invention is an improved harrow; and it consists in the peculiar construction and combination of devices hereinafter fully described and claimed.

15 The object of my invention is to provide a flexible beamless harrow the teeth of which are movable vertically independently of each other to adapt the harrow to conform to inequalities in the surface of the soil, and hence 20 increase the efficiency of the harrow.

One object of my invention is to effect improvements in the construction of the harrow-teeth.

Another object is to combine a plurality of 25 the harrow-teeth with link devices which flexibly connect them together.

In the accompanying drawings, Figure 1 is a top plan view showing a portion of a harrow constructed in accordance with my invention. Fig. 2 is an elevation of the same. Fig. 3 is a view similar to Fig. 1, showing a modified construction of the harrow. Figs. 4 and 5 are detail views showing modified 30 constructions of the links which connect the harrow-teeth together, and Fig. 6 is a similar view showing a modified form of harrow-tooth.

In the preferred form of my invention (shown in Fig. 1) each of the harrow-teeth 1 is polygonal in cross-section, has concaved 40 sides 2 formed with sharpened cutting edges 3 at the angles, and the ends of the tooth are pointed, as at 4, so that either end of the tooth may be used. Midway, or substantially so, between the ends of each harrow-tooth the same is provided with radially-projecting ears 5, which are formed integral with the tooth, and the said ears are provided 45 with transverse openings 6, adapted for the reception of link devices 7, which are employed to connect the teeth together in series and in such manner that each harrow-tooth

is movable vertically independently of the others. The harrow-teeth and the link devices 7, which connect them flexibly together, 55 constitute a flexible harrow fabric which is adapted to conform perfectly to inequalities in the soil when the harrow is in operation, so that the depressed portions, ruts, and the like in a field will be harrowed effectually, as 60 well as the more elevated portions of the field. The front row of harrow-teeth may, as here shown, be flexibly connected to a draw-bar *a* by means of hooks or similar devices *b*; but any approved means may be employed for 65 drawing the harrow across a field, and I do not limit myself in this particular.

In the form of my invention shown in Fig. 3 the harrow-teeth 1^a are triangular in cross-section and the sides 8 thereof are flat. Each 70 harrow-tooth has at its front edge at a point, intermediate its ends an opening 9 and is provided on its rear side with a rearwardly-projecting lug 10, having an opening 11. The link devices employed in this form of my invention are rods 12, of suitable length, which are passed through the openings 11 and are provided with rearwardly-extending offset 75 portions 13, which engage the openings 9. It will be observed by reference to Fig. 3 that 80 the harrow-teeth 1^a are disposed in rows one behind another and that the harrow-teeth are set alternately, so that each harrow-tooth is directly opposite and in front of the space between two harrow-teeth behind it. 85

By connecting the link devices to the intermediate portions of the harrow-teeth and pointing both ends of the latter, as herein described, the harrow-teeth may be used with either side down, so that its efficiency is very 90 greatly prolonged. It will be further understood that in the event that a harrow-tooth or link device becomes broken the same can be readily replaced at very small cost.

I do not desire to limit myself to the precise construction and combination of devices herein shown and described, as it is evident that modifications may be made therein without departing from the spirit of my invention and within the scope of the appended 95 claims.

Having thus fully described my invention, what I claim as new, and desire to secure by Letters Patent, is—

1. A harrow comprising a plurality of teeth each having openings between its ends, and links flexibly engaged with said openings and each connecting a plurality of the teeth together, substantially as described.
2. A harrow comprising a plurality of teeth each provided on its front and rear sides with openings between its ends, and links engaged with said openings and each connecting a plurality of the teeth together, the axes of the teeth being substantially central with relation to the links, substantially as described.
3. A harrow comprising teeth each provided on its front and rear sides with openings between its ends, and arranged in rows, the teeth of the respective rows being opposite the spaces between the teeth of the adjacent rows, and link-rods extending transversely

of the harrow and each engaged with the rear openings of a plurality of the teeth of one row and the front openings of a plurality of the teeth of the following row, substantially as described.

4. A harrow comprising alternately-disposed teeth and links, the former having openings between their ends engaged by the links, and having their axes substantially central with relation to the links, substantially as described.

In testimony whereof I have hereunto set my hand in presence of two subscribing witnesses.

GEORGE D. SCHLOSSER.

Witnesses:
